UNITED STATES PATENT OFFICE.

PHILIP YEAGER, OF OTTERVILLE, IOWA.

DRAFT-EQUALIZER.

SPECIFICATION forming part of Letters Patent No. 722,347, dated March 10, 1903.

Application filed December 18, 1902. Serial No. 135,771. (No model.)

To all whom it may concern:

Be it known that I, PHILIP YEAGER, a citizen of the United States, residing at Otterville, in the county of Buchanan and State of Iowa, have invented certain new and useful Improvements in Draft-Equalizers; and I do hereby declare the following to be a full, clear, and exact description of the invention, such as will enable others skilled in the art to which it appertains to make and use the same.

My invention relates to draft-equalizers; and it consists of certain novel features of combination and construction of parts, the preferred form or materialization whereof will be hereinafter clearly specified, reference being had to the accompanying drawings.

The object of my invention is to provide an evener or draft-equalizer which will be found useful for a great variety of purposes, where-
20 by three or four horses or a larger number thereof may be properly connected to a wagon-
binder or the like with the assurance that the draft will be properly distributed among the draft-animals, so that each will be required
25 to perform its part of the work.

A further object of my invention is to dis-
pose the line of draft laterally or to one side
30 of the tongue or the common center of draft
of the vehicle or machine, so that there will
35 be no lateral strain placed upon the animals—
as, for instance, the placing of two animals
upon one side of the tongue and one animal
upon the other side.

Other objects and advantages will be here-
35 after made clearly apparent, reference be-
ing had to the accompanying drawings, which
are made a part of this application, in which—

Figure 1 shows a top plan view of an ordi-
nary wagon or reaper tongue with my draft-
40 equalizer applied to use thereon. Fig. 2 is a
view showing a portion of the evener-tree and
its supporting-bracket in section. Fig. 3 is a
perspective detail view of the supporting-
45 bracket complete shown in Fig. 1.

Numerals will be employed to designate the
various details of my invention and coöper-
40 ating accessories, the same numerals refer-
ring to a similar part throughout the several
views.

In carrying out my invention I attach to the
tongue 1 of the vehicle the anchoring-plate 2,
designed to rotatably hold in place the pulley

3, around which extends the anchoring-chain
4, each end of which is connected in any pre-
ferred way to the rear end of the clip-sections 55
or clevises 5, carried by each end of the evener-
tree proper, 6, which latter is provided near
its central portion with the bolt 7, designed
to pass loosely through the slotted aperture
8, formed in the extreme outer or free end of 60
the bracket 9, which latter is anchored in po-
sition upon the tongue by means of the bolts
10 or the equivalent thereof. The bolt 7 is
provided on its lower end with a suitable en-
largement or head, by which it will be held 65
against casually slipping out of place. Each
end of the bracket 9, it will be observed, is
provided with a radially-disposed slot 11,
whereby the bracket may be relatively ad-
justed with respect to the tongue, so that the 70
slot 8, formed in the outer end of the bracket,
may be disposed in a plane truly parallel with
the tongue or at any preferred angle thereto,
the object of which will be hereinafter more
clearly set forth.

Each of the clevises 5 extends forward and
affords means to pivotally connect the double-
trees 12 thereto, as by means of the bolt or
rod 13, while each of said doubletrees is pro-
vided with the singletrees 14, as shown in 80
Fig. 1, and to which the draft-animals may
be connected in the usual manner.

By the arrangement herein described it
will be observed that the main office per-
formed by the slotted aperture 8 is to confine 85
the bolt 7 within proper bounds relative to
the tongue, though permitting a reasonable
play of said bolt and incidentally permitting
a similar movement of the tree 6 during the
use thereof.

The chain 4, it will be observed, will there-
fore be left to play freely around the pulley
3, whereby compensation may be thus afford-
ed for the varying position of the draft-ani-
mals and at the same time confines the for- 95
ward and rearward movement of the bolt 7
within the space afforded by the slotted open-
ing 8.

Having thus fully described my invention,
what I claim as new, and desire to secure by 100
Letters Patent, is—

1. The herein-described draft-equalizer
comprising the combination with the tongue
of a vehicle, of a bracket adjustably secured

to said tongue; and having its outer end provided with a slot longitudinally disposed with regard to said tongue; a main tree having a bolt extending through said slot, a pulley-
5 wheel secured to the tongue in the rear of the bracket; a chain each end of which is connected to said tree and extended around said pulley whereby the bolt of said tree will be permitted to play within said slot during the
10 operation thereof and thereby provide compensation for the movement of the tree relative to the tongue, all combined substantially as specified and for the purpose set forth.
15 2. In an evener of the character specified, the combination with the tongue or frame of

a vehicle, of a bracket having a bifurcated inner end each branch of which is provided with a radial slot; means to adjustably secure said branches to the frame or tongue whereby it may be relatively adjusted with respect thereto, said bracket having at its outer end a slotted opening normally disposed in a plane parallel with the tongue as and for the purpose set forth. 20

In testimony whereof I affix my signature 25 in presence of two witnesses.

PHILIP YEAGER.
